By *Baldwin Vale* Attorney

UNITED STATES PATENT OFFICE.

WILLIAM W. FORBIS, OF SAN FRANCISCO, CALIFORNIA.

TOOL.

1,413,110.

Specification of Letters Patent. Patented Apr. 18, 1922.

Application filed August 4, 1920. Serial No. 401,239.

To all whom it may concern:

Be it known that I, WILLIAM W. FORBIS, a citizen of the United States, and a resident of the city and county of San Francisco, 5 State of California, have made a new and useful invention—to wit, Improvements in Tools; and I do hereby declare the following to be a full, clear, concise, and exact description of the same.

10 This invention relates particularly to an improved gripping device of the wrench type.

An object of this invention is to provide a device having a free movement between the respective gripping parts within a predetermined limit and having an automatic or self-adjusting action of the gripping jaws, that will exert a grip or squeeze on an object proportional with the 20 leverage force exerted on the handle, as contrasted with the manually adjusted "pipe" and "monkey" wrenches; and to provide a device of this character that is simple and efficient in its construction and operation. 25 and economical to manufacture. Other objects and advantages will appear as this description progresses.

In this specification and the annexed drawings, the invention is illustrated in the 30 form considered to be the best, but it is to be understood that the invention is not limited to such form, because it may be embodied in other forms, and it is also to be understood that in and by the claims following 35 the description it is desired to cover the invention in whatsoever form it may be embodied.

In the accompanying one-sheet of drawings, Figure 1 is a front end elevation of a 40 tool constructed in accordance with my invention.

Figure 2 is a side elevation of the same.

Figure 3 is a rear end elevation of Figure 2.

45 Figure 4 is a side elevation of my improved wrench, partly in section and opened to illustrate it in operative position.

Figure 5 is a plan section taken on line 5—5 of Figure 2.

50 In detail the construction illustrated in the drawings includes a handle 1 of any length, shape or weight desired, having an end 2 thereof surfaced to form parallel side walls. The end 2 of the handle terminates 55 in a rounded end as at 3 and is provided with a hole drilled axially therethrough.

The gripping jaw 4 comprises a channel or substantially U-shaped member of which the base portion 5 is serrated, to facilitate its clinging or holding to an object. The side 60 walls 6 and 7 of this jaw are adapted to straddle the parallel side walls of the handle 2 and pivotally engage by the pin 8, passing through the side flanges of the jaw 4 and the handle end 3. The free end of the gripping 65 jaw 4 is provided with an opening 9 through the base portion 5 thereof and has the abutment 10 enclosing the end of the channel.

An opposed gripping jaw 11 is mounted in juxtaposition with the gripping jaw 4 and 70 has part of its lower face serrated as at 12. The underside of the jaw 11 is provided with a depending extension 14, that is adapted to register with the opening 9 in the lower jaw 4, and is of less thickness than the jaw 75 11 and has the end 15 thereof further reduced leaving a shoulder 16 on each side thereof, equal in height to the thickness of the links 17. The links 17 are pivotally connected by the pivot pin 18 to the extension 80 14 on both sides of the reduced end 15 leaving the outer surfaces thereof flush with the side surfaces of the extension 14 and free to slide through the aforementioned opening 9 in the lower gripping jaw. The links 17 85 have the opposite ends thereof pivotally mounted on the handle 1 at 19.

This device operates as follows:

The handle 1, as illustrated in Figure 2, is grasped by the hand of an operator and 90 by a slight swinging action thereof, the opposed jaws 4 and 11 are designated, moving into an opened position such as illustrated by Figure 4. If no care is taken in regulating the amount of opening of the gripping 95 jaws, the same will ordinarily open to their widest capacity. Regulation of the width of opening of the gripping jaws is obtained by moving the pivoted lower clutch jaw either upwardly or downwardly relative to 100 the handle 1. This movement of the lower jaw acts to adjust the relative positions of the opposed gripping jaws by reason of the extension 14 and links 15 being slidably guided within the opening 9 of the lower 105 gripping jaw. Thus a movement of either gripping jaw will move the opposed jaw proportionately. It will be noted that the links 17 are connected to the extension 14 substantially intermediate the ends thereof 110 permitting the rounded terminus of the reduced end 15 to bear against the inside of the

handle 1 as at 20, preventing the lower jaw from locking the extension 14 in the wide open position. The serrated faces 5 and 12 of the respective gripping jaws are so positioned, that any movement of the lower jaw 4 and corresponding movement of the upper jaw 11, through its articulated connection with the handle 1, that the jaws in opening will be maintained substantially in parallel relation, thus permitting the tool to be used on objects of any shape without further means of adjustment.

Having thus described my invention, what I claim and desire to secure by Letters Patent is—

A tool such as described comprising a

handle; a jaw, having an extension thereon, and a link pivotally connected to said handle and to said jaw extension intermediate the ends thereof; and an opposed jaw pivoted to said handle having an opening through the free end thereof slidably guiding said jaw extension and link therein and means whereby the free end of said jaw extension slidably contacts with the handle.

In testimony whereof, I have hereunto set my hand at San Francisco, California, this 30th day of June 1920.

WILLIAM W. FORBIS.

In presence of—
LINCOLN V. JOHNSON.
